Patented June 6, 1916.

UNITED STATES PATENT OFFICE.

WILLIAM VINCENT MOORE, OF NEW YORK, N. Y.

GUN-TAMPION AND MEANS FOR ACTUATING THE SAME.

1,186,023.

Specification of Letters Patent. Patented June 6, 1916.

Application filed September 22, 1915. Serial No. 51,992.

To all whom it may concern:

Be it known that I, WILLIAM V. MOORE, a citizen of the United States, and a resident of the city of New York, borough of 5 Manhattan, in the county and State of New York, have invented a new and Improved Gun-Tampion and Means for Actuating the Same, of which the following is a full, clear, and exact description.

10 This invention relates to attachments for guns and particularly to a gun tampion or plug and means for actuating the same, and has for an object the provision of an improved construction whereby the muzzle of 15 the gun is normally closed but is opened immediately before the charge is exploded.

Another object in view is to provide a mechanism for actuating the tampion of a gun whereby the same is quickly opened immediately before the discharge and closed 20 immediately after the discharge, thereby preventing the inflow of water in case the gun is near the water line.

A still further object in view is to provide 25 a mechanism for operating the tampion of a gun in connection with the discharge mechanism of the gun whereby upon the closing of the circuit for discharging the gun the mechanism for operating the tampion will be 30 first actuated and then the mechanism for causing the explosion will be actuated.

In the accompanying drawings: Figure 1 is a longitudinal vertical section through a gun and associated parts disclosing an embodiment of the invention; Fig. 2 is a transverse section through Fig. 1 on line 2-2; Fig. 3 is an enlarged longitudinal vertical section through an air valve disclosed in Fig. 1.

40 Referring to the accompanying drawings by numerals, 1 indicates a gun of any desired construction and 2 the breech block of any desired form, which is provided with a firing mechanism 3 of any suitable form operated 45 by an electrical current. On the drawing a firing pin and a solenoid are shown but this construction is merely disclosed in order to show an operative form as any suitable construction connected with the wires 4 and 5 would answer the purpose of the invention. 50 Wire 4 is connected with a contact member 6 while wire 5 is connected to battery 7. Battery 7 is also connected with contact 8 carried by rod 9 whereby when rod 9 is moved 55 so that contact 8 will engage contact 6 the circuit of wires 4 and 5 together with the

parts connected therewith will be closed and the firing mechanism 3 will be actuated. In order that the rod 9 may properly operate a core 10 is mounted thereon, which core is 60 adapted to be moved by solenoid 11, which solenoid is energized by current from battery 12 when the switch 13 is closed.

Rod 9 is mounted to slide in supporting brackets 14, 15 and 16 carried by gun 1 and is normally held in the position shown in Fig. 1 by spring 17 acting on bracket 16 and on a stop 18 rigidly secured to the rod. The forward end of rod 9 is preferably bifurcated so that the lower end of lever 19 may extend therein, a pin 20 being connected with the bifurcated end of rod 9 and extending through slot 21 in lever 19, which lever is pivotally mounted at 22 on bracket 14 and rigidly connected with the plug or 70 tampion 23. A suitable check valve 24 is arranged in the tampion 23 for allowing any excess air or gases in the gun 1 to escape after the tampion 23 has been closed. Arranged on the rod 9 near the bracket 15 is a cam 25 which is adapted to engage roller 26 positioned on the lower end of the stem 27 of valve 28 whereby valve 28 is raised and unseated when cam 25 is moved to the dotted position shown in Fig. 1. A spring 29 normally holds the valve 28 seated so that cam 25 must act against this spring. Valve 28 is interposed in a pipe 30, which pipe is connected with an air storage tank. When valve 28 is raised compressed air passes 80 from valve 28 into the pipes 31 and 32, which pipes extend into the gun 1, as shown in Fig. 2, so as to discharge air therein after the projectile has moved out of the gun. A check valve 33 is preferably provided between valve 28 and the pipes 31 and 32 so as to prevent the escape of gas through these pipes. The check valve 33 is intended to allow the air from pipe 30 to freely pass into the gun 1 after the projectile has escaped 90 and also after part of the gases have escaped so as to blow out the remaining part of the gases and act as a cleaning medium as well as means for preventing water from entering the gun before the tampion 23 can be reseated. Preferably the pipes 31 and 32 enter 100 gun 1 immediately in front of the front end of the cartridge carrying the projectile so that the air may freely escape into the gun barrel as soon as the pressure therein has 105 been reduced to a point below the pressure of air from pipe 30.

2.

In operation, after the gun has been sighted and it is desired to discharge the same, switch 13 is closed, which will cause the energization of solenoid 11 and consequently the rearward movement of the rod 9. The rod 9, by its rearward movement, will cause the tampion 23 to move to the dotted position shown in Fig. 1 by the time contact 8 engages contact 9. Upon the engagement of the contacts just mentioned the firing mechanism 3 will be operated and the charge immediately exploded thereafter. As cam 25 moves to the rear with rod 9 air is turned on at approximately the same time that the discharge takes place, so that the compressed air is ready to enter as soon as most of the gases have escaped. By the use of the air a double function is secured, namely, a cleaning element is introduced into the barrel and also means for preventing the entrance of water. As soon as the switch 13 is opened after the firing, solenoid 11 will be deenergized and spring 17 will then act for restoring the parts to the position shown in Fig. 1. The gun must then be reloaded and if desired may be cleaned in the usual manner.

The detail construction of the gun and the firing mechanism form no part of the present invention so that the same are merely shown conventionally to illustrate the co-action of said parts with the tampion and mechanism for actuating the same.

What I claim is:

1. In a device of the character described, the combination with a gun, of a tampion or plug therefor, means for pivotally mounting said tampion, a reciprocating rod for moving said tampion so as to close said gun and to move the tampion so as to leave the front of the gun exposed, a spring for moving said rod in one direction, a solenoid for moving the rod in the opposite direction, and means operated by said rod when the same is actuated by said solenoid for causing the operation of the firing mechanism of said gun.

2. In a device of the character described, the combination with a gun provided with an electrically operated firing mechanism, of a tampion for the gun, a reciprocating rod for moving said tampion to an operative and inoperative position, a spring for moving said rod so that the tampion will be moved to an operative or closed position, a solenoid for moving said rod so that the tampion will be moved to an inoperative or open position, and means operated by said rod when the same is actuated by the solenoid for closing

the circuit of said firing mechanism, said means being actuated as said rod approaches its extreme movement, whereby the firing mechanism is not actuated until after the tampion has been removed.

3. In a device of the character described, the combination with a gun, of a tampion, means for pivotally supporting said tampion whereby the same may be moved to a position for covering the muzzle of said gun and moved to a position out of the way of said gun, a lever extending from said tampion for actuating the same, said lever being provided with a slot, a reciprocating rod, said rod being provided with a pin extending through said slot whereby when said rod is moved back and forth the tampion is opened and closed, a spring acting on said rod to normally hold the same in such a position as to maintain the tampion closed, a core member connected with said rod, a solenoid adjacent said core member and adapted to act thereon for maintaining said rod against the action of said spring for opening said tampion.

4. In a device of the character described, the combination with a gun, of a tampion for the muzzle thereof, a reciprocating rod for moving said tampion so as to engage said muzzle and be moved therefrom at will, an electrical member for moving said rod so as to remove the tampion from the said muzzle, and means actuated by said rod for switching on air under pressure to the bore of said gun.

5. In a device of the character described, the combination with a gun, of a pivotally mounted tampion for the muzzle thereof, a rod for actuating said tampion, a spring acting on said rod for holding the same normally in a position for maintaining the tampion against the muzzle of said gun, an electrically operated member for actuating said rod so as to move the tampion from said muzzle, an electrically operated firing mechanism for said gun, and means mounted on said rod and acting to close the circuit of said electrically operated firing mechanism when said rod has been moved for opening said tampion.

In testimony whereof I have signed my name to this specification in the presence of two witnesses.

WILLIAM VINCENT MOORE.
